[57] CLAIM

The ornamental design for a combined perfume bottle and closure, as shown and described.

DESCRIPTION

FIG. 1 is a perspective view of a combined perfume bottle and closure showing my new design;

FIG. 2 is a side perspective view of the combined perfume bottle and closure shown with the closure in an open position;

FIG. 3 is a front elevation of FIG. 1, the rear elevation being the same;

FIG. 4 is a side elevation of FIG. 1, the opposite side being the same; and

FIG. 5 is a top plan view of FIG. 1.
